UNITED STATES PATENT OFFICE.

WILLIAM J. PATTERSON AND CHARLES R. KNAPP, OF PITTSBURG, PENNSYLVANIA, ASSIGNORS TO HEYL AND PATTERSON INCORPORATED, OF PITTSBURG, PENNSYLVANIA, CHARTERED UNDER THE LAWS OF PENNSYLVANIA.

METHOD OF REUSING MOLDING-SAND.

SPECIFICATION forming part of Letters Patent No. 793,089, dated June 27, 1905.

Application filed July 18, 1904. Serial No. 217,015.

To all whom it may concern:

Be it known that we, WILLIAM J. PATTERSON and CHARLES R. KNAPP, residents of Pittsburgh, in the county of Allegheny and State of Pennsylvania, have invented a new and useful Improvement in Methods of Reusing Mold-
ing-Sand; and we do hereby declare the following to be a full, clear, and exact description thereof.

Our invention relates to a method of reusing molding-sand where a continuous process of molding is employed.

In all foundry plants the sand used in making the sand molds is used over and over again, the practice being that after the castings are removed from the molds on the dumping-floor to temper the sand with water until it is of the proper consistency, screen the same, and again return it to the molding-room. It has been found that under certain conditions this sand when used over and over again in this way becomes full of small globules or kernels which produce a roughness on the mold-face, so that the castings formed therein are liable to present a rough surface. Many different theories have been advanced as to the cause of the formation of these globules or kernels, but from whatever cause they always appear in sand that has been used over and over again too frequently; and it is the object of our invention to so treat the sand that these globules or kernels will be avoided and the quality of the sand maintained so as to produce castings with smooth and even surfaces.

To this end our invention consists in dividing the sand into separate portions, using the sand of one portion continuously during a certain period by conveying it to the molds and returning it again, allowing the sand of said portion to remain in a state of rest after such a period of use, using the sand from another portion in the same manner for a certain period, and so on using from each portion and finally returning to the first portion.

In the accompanying drawings we have shown an arrangement of a foundry plant

provided with means for carrying out our method.

In the drawings, Figure 1 is a plan view, 50 and Fig. 2 is a side elevation.

In the drawings the numeral 2 designates the molding-floor, upon which are located the molding-machines 3, which may be of any suitable construction. Arranged at a suitable distance above the molding-machine is a conveyer 4 of the well-known type consisting of a reciprocating carrier with hinged flights secured thereto. Leading from the conveyer 4 to the molding-machines 3 are the spouts 5, which are controlled by gates 6. The conveyer 4 extends over the storage-bins 7 8 9 10 11 12, and gates 13 in said conveyer are adapted to discharge the sand from said conveyer into said bins.

Located over the conveyer 4 is the rotary screen 14, the sand being fed to said screen by a chute 15 at the upper end of the elevator 16. The lower end of the elevator 16 is preferably below the foundry-floor, and at the 70 lower end of said elevator is the hopper or boot 18.

Below the storage-bins 7 8 9, &c., is the conveyer 19, which is adapted to discharge into the hopper 18 of the elevator 16. The 75 bins 7 8 9, &c., are provided with openings 20, by means of which the sand is withdrawn from said bins onto the conveyer 19 to be carried to the hopper 18, said openings being provided with suitable gates.

Running parallel with the molding-floor is the flask-conveyer 21, upon which the flasks are placed when removed from the molding-machines. These flasks are carried around to a point about opposite the hopper 18, where 85 they are removed, and at this point the molds are dumped onto the dumping-floor, where the castings are separated from the sand and the sand then shoveled into the hopper 18.

In the practice of our invention the storage-bins 7, 8, 9, 10, 11, and 12 are filled with molding-sand, and the sand is first taken from the bin 7. The opening 20 at the lower end of said bin is open to permit the sand to be dis-

2

charged onto the conveyer 19, which conveys said sand to the hopper 18, where it is elevated by the elevator 17 and discharged into the screen 14. Just previous to passing into the screen it is customary to temper the sand by the addition of water, which may be introduced by a suitable pipe 23. The sand passes from the screen onto the conveyer 4, whence it is carried to the molding-machines 3, the gates 13 leading to the storage-bin being closed. The sand having been introduced into the molding-machines and the molds having been formed, the flasks are then transported to the flask-conveyer 21, whence they are carried around to the dumping-floor 22. Here the flasks are removed and the castings taken from the molds, while the sand is shoveled into the hopper 18 and carried up and into the screen 14, after being tempered by water admitted by pipe 23. The screen 14 acts to sift the sand and prevent any bits of castings or other objects from passing with the sand into the conveyer. The sand passes from the screen into the conveyer 4 and is carried to the bin 7. The gate 13 of the bin 7 is opened and the sand discharged into said bin on the top of the sand already therein. The gate 13 is then closed and the gate 20 opened, whereupon a portion of sand is removed from the bottom of the bin 7 and carried by the conveyer 19 to the molding-machines 3 for the next molding operation. This operation is continued for a certain period, all the molds during that period being made from sand taken from the bin 7 by using that sand over and over again. We have discovered that sand may be reused in the molds for a certain period without the formation of the globules and kernels hereinbefore referred to, and we continue to use the sand from the bin 7 during such period—say, by way of illustration, for a day's run. We have, moreover, discovered that by allowing this used sand to remain in a state of rest for a certain period the tendency of the sand to form globules or kernels is avoided. Accordingly after the sand in the bin 7 has been used for a day's run we commence the next day by using sand from the bin 8 and continue that day with such sand from the bin 8. On the next succeeding day we use the sand from the bin 9, and so on in rotation throughout the bins 10, 11, and 12. By the time we have used the sand from bin 12 the original portion of sand in bin 7 has been allowed to rest, and during such period has been relieved of the liability of the for-

mation of globules, so that on returning to bin 7 and taking the sand therefrom it will be found that the sand may be used continuously for a like period without the formation of globules.

We have illustrated six bins for separating the sand into different portions, working one bin each day, so that in the six working days of a week each bin will be worked from once. It may not be found necessary, however, to use so many portions or bins, and in the practice of our method we do not wish to limit ourselves to the number of bins employed. In some cases it may be found that twenty-four hours' rest will suffice to bring the sand into proper condition for reuse. By our method, therefore, the sand may be used over and over again without the employment of rolls or other grinding devices for crushing up the globules, while at the same time the sand by being allowed to remain in a state of rest does not become worn out so readily and retains more of its original consistency.

80 What we claim is—

1. The method of reusing molding-sand, consisting in dividing the sand into separate portions, using one portion continuously during a certain period by conveying sand therefrom to the molds and returning it to said portion after use to be used over again, allowing the sand to remain in a state of rest after such period of use, using sand from another portion in the same manner for a certain period, and so on, and finally returning to the said first portion again.

2. The method of reusing molding-sand, consisting in dividing the sand into separate portions, using one portion continuously during a certain period by conveying the sand from the bottom of said portion to the molds and returning the same to the top of said portion after use to be used over again, allowing the sand to remain in a state of rest after such period of use, using sand from another portion in the same manner for a certain period, and so on, and finally returning to the said first portion again.

100 In testimony whereof we, the said WILLIAM J. PATTERSON and CHARLES R. KNAPP, have hereunto set our hands.

WILLIAM J. PATTERSON.
CHARLES R. KNAPP.
